UNITED STATES PATENT OFFICE.

ALEXANDER LEUNIS, OF STAPLETON, NEW YORK, ASSIGNOR TO AMCOR ADVERTISING INCORPORATED, OF NEW YORK, N. Y., A CORPORATION OF NEW YORK.

METHOD OF MAKING DISPLAY SHEETS.

Application filed May 5, 1926. Serial No. 106,804.

This invention relates to improvements in advertising and other display devices and the method of making the same.

An object of the invention is to provide a display sheet which may be utilized for advertising purposes and produced at a minimum cost, and wherein a corrugated surface of the sheet has indicia applied thereto, such as a design, pictorial representation, or other suitable data, and which sheet is adapted for arrangement in display windows, as counter or pillar trims, wall friezes and the like, in such manner that the indicia thereon will be legible from all angles of vision.

Another object is to apply indicia in distorted form to a surface of a foundation sheet and thereafter alter the configuration of said surface in such manner that the indicia will be restored to its natural or normal condition.

A further object resides in placing a design upon a sheet of material which is then stretched to distort said design, whereupon the latter is transferred in its distorted form to a foundation sheet which is then corrugated to restore the design to its normal appearance.

The above and other objects will appear more clearly from the following detail description, when taken in connection with the accompanying drawings, which illustrate a preferred embodiment of the inventive idea.

In the drawings—

Figure 1 is a fragmentary plan view of a sheet illustrating the first step in the method;

Figure 2 is a similar view of said sheet showing the design thereon in distorted form;

Figure 3 is a plan view illustrating the design transferred in distorted form to the foundation sheet;

Figure 4 is a similar view of the sheet illustrated in Figure 3 after the same is corrugated; and

Figure 5 is a longitudinal section of Figure 4.

In carrying out the present method a sheet of material 6, preferably translucent and having elastic qualities, such as crepe paper, is secured in an unstretched condition to a frame of any desired construction which may be adjusted in length and width for a purpose which will presently appear. Another

sheet (not shown) having suitable indicia thereon, such as a design or other representation, is now placed under the sheet 6 and traced on to the latter sheet by means of soft crayon. Although a complete design is shown on the sheet 6, it will be understood that in actual practice it is only necessary to trace the outlines of the design during this step of the method. When the tracing is completed the sheet 6 is stretched longitudinally, as indicated by the arrows in Figure 2, by adjusting the frame to which the sheet is secured thereby distorting the design, as indicated. The sheet 6 is stretched longitudinally when the corrugations in the foundation sheet upon which the design is ultimately placed extend transversely or vertically of the sheet, but it will be understood that if these corrugations are to run longitudinally of the foundation sheet, the sheet 6 should be stretched transversely or vertically by proper adjustment of the frame so as to distort the design in a direction at right angles to that shown in Figure 2. It has been found in actual practice that the sheet 6 should be stretched to increase its length from about forty-five to fifty per cent, but the amount of stretching is dependent upon the size or width of the corrugations made in the foundation sheet. For example, if the sheet 6 is normally thirty-six inches in length the same, after being stretched, should be approximately fifty-two inches long. The proper amount of stretching may be readily accomplished by providing the frame upon which the sheet 6 is mounted with a suitable scale.

After the tracing and stretching operation of the sheet 6 is performed a sheet of ordinary tracing paper or the like is laid upon the sheet 6 and pressure is applied to said sheets, by rubbing or otherwise, to transfer the outlined design from the sheet 6 to the tracing paper, this transfer being made possible by the use of soft crayon in the original tracing. The design now appears on the tracing sheet in a reversed position and is now heavily outlined to make the same distinct. After this is done the outline of the design is again transferred to another sheet, such as a sketch board, by tracing over the design on said tracing sheet and the design may then be completely filled in in ink, as shown in the drawings.

By ordinary lithographing or printing

- processes the design is again transferred to a surface of a flat foundation sheet 7, as shown in Figure 3. The sheet 7 may be multiple ply material such as ordinarily used for corrugated paper and may ultimately be corrugated upon both surfaces if it is desired to apply the design to said surfaces. However, as shown in Figure 5, the backing 8 may be flat while the facing 9 only is corrugated.
- 10 Following the application of the design in its distorted condition to the facing of the sheet 7 the latter is corrugated and the design will, as a matter of course, then extend coincident with the contour of the corrugations, or, in other words, over the ridges and into the furrows of the foundation sheet. In so doing the design will be restored to its normal or original appearance, as shown in Figure 4.
- 15 20 In actual practice the foundation sheet 7 may be made up of a plurality of units having repeats of the desired design thereon so that a roll of the sheet, for instance one thousand yards in length, may be prepared.
- 25 This will enable any particular advertiser, for example, to order any desired length of the product and permit him to divide the same into suitable lengths for display purposes in various places, such as show windows, pillar or counter trims, wall friezes and the like. In order to prepare a length of the product such as described, a plurality of foundation sheets or units 7, in their normal or flat condition, are prepared and each
- 30 35 unit is of substantially the same length and width as the sheet 6 in its stretched condition. After the design has been transposed to the flat units 7, the latter are properly trimmed.

and placed with adjacent ends overlapping so as to register any parts of the design extending to the ends of the units with similar parts of said design on adjacent units; and the overlapped ends are then glued together and compressed so that said units will combine to form one continuous strip. Said strip is then rolled up and fed into a corrugating machine to corrugate the surface carrying the design.

It will, of course, be understood that various methods may be employed for transferring the design in its distorted form on to the flat surface of the foundation sheet 7. For instance, instead of securing on tracing paper an impression of the distorted design from the sheet 6 and ultimately transferring said design onto sketch board for lithographing or printing purposes in the manner set forth, it may be possible to trace the design directly onto the sketch board and thereby eliminate intermediate steps in the method.

What is claimed is:

The method of making an advertising or other display sheet, which consists in tracing a design on to a sheet having elastic qualities, stretching said sheet to distort the design thereon, transferring the distorted design to a tracing sheet, retransferring the design from the tracing sheet on to a third sheet, again transferring the design from said third sheet to a surface of a foundation sheet, and then corrugating said surface to restore the design to its normal appearance.

In testimony whereof, I have affixed my signature.

ALEXANDER LEUNIS.
